UNITED STATES PATENT OFFICE.

JOHN W. NASMITH, OF MANCHESTER, ENGLAND.

COMBING MACHINE.

Original application filed March 30, 1922, Serial No. 548,209. Divided and this application filed January 17, 1923. Serial No. 613,203.

To all whom it may concern:

Be it known that I, JOHN WILLIAM NASMITH, a subject of the King of Great Britain, residing at Manchester, in the county of 5 Lancaster, England, have invented a new and useful Improvement in Combing Machines, of which the following is a specification.

In Nasmith and other combing machines 10 the feeding of the material is usually performed by a feed roller carried in the nipper and resting on the bottom nipper plate or dish or on a second roller and during the forward movement of the nipper the roller 15 is caused to turn and feed the necessary amount of material forward each stroke during the detaching period. During the detaching operation a considerable amount of long fibre, which is not carried forward 20 by the detaching rollers, is drawn out of the nipper and crumpled up behind the top comb and not being held by the nipper when it closes is carried away as waste.

The object of the invention of this application 25 which is a division of an earlier case Serial Number 548,209, filed March 30, 1922, is to save this unnecessary waste by causing the feed apparatus to draw back a short length of the previously fed material within 30 the nipper as it commences to recede from the detaching rollers and before it closes and this may be done by employing the usual feed roller operated in the following manner, about to be described with reference to 35 the drawings.

Fig. 1 represents an end elevation of part of the nipper of a Nasmith combing machine when it is in its position at the rear-most end of its stroke and Fig. 2 shows the 40 same when in its most forward position with the addition of those parts to operate the feed roller as required by this invention.

Referring first to Fig. 2, the combing cylinder is represented by 1, the detaching roller by D and the nipper shaft by W. The 45 connection between this shaft and the nipper cheeks N² is as shown. The shaft W is rocked in the usual way and swings the nipper cheeks (one at either end of the 50 nipper) the nipper bridge B and the lower jaw P² uninterruptedly to and fro between the position shown in Fig. 1 and that shown in Fig. 2 that is between the dotted radii C and C¹ along the dotted arc C². The feed

roller F, mounted in the usual manner in 55 spring-weighted adjustable bearings, rests on the nipper plate P², and has mounted on one end of it a pinion P. The toothed sector S, whose center is at N when in gear with the pinion P is hinged on a stud 38^a 60 fixed on a convenient part of the framing of the machine not shown in the drawing. Pivoted at 39^a on the sector S is the link 40, having fixed in its upper end a threaded pin 40^a which passes through the block 41 65 swivelling freely in the end of the lever 42, one of which is keyed on the shaft T³ in each head of the machine. Nuts 43 and 44 serve to regulate the proper engagement of the sector with the pinion. The shaft T³ 70 is rocked in the following manner. A pin 48 is fixed to the framing of the machine and on it swings a lever 47 having a bowl at the end which rolls on the cam M mounted at the end of the machine on the cylinder 75 shaft. A link 46 connects the bowl and lever to the lever 45 keyed on the end of the shaft T³. One end of a spring 50 is attached to the end of the lever 45 and the other end of the spring is secured to a pin 51 fixed to the 80 frame of the machine so that the pull of the spring always maintains the bowl in contact with the periphery of the cam M.

The cam M is so shaped that when part of the forward stroke of the nipper has 85 taken place, it drops the sector into gear with the pinion and turns the roller forward during the remainder of the forward stroke of the nipper and it keeps the sector in gear with the pinion until the nipper has 90 receded a short distance from the detaching rollers, the effect of which is to turn the roller slightly backwards and to draw back from behind the top comb, (not shown in the drawing to avoid complication) and into 95 the nipper before it closes, a short length of the previously fed material. At a given moment in the receding motion of the nipper the sector is raised by the cam M at the appropriate instant and the roller ceases to 100 turn backwards and remains stationary on the plate until the sector is again dropped in on the next forward movement of the nipper.

Although the drawings show and the 105 specification describes the invention applied to a combing machine constructed according to my United States Patent No.

1,369,532 it will be understood that such a feed apparatus can equally well be applied to other similar types of combing machines.

Claim.

5 In a combing machine of the Nasmith type, a swinging nipper, a feed roller mounted on the lower jaw thereof, a toothed pinion on the end of the said roller, a 10 toothed sector to engage and disengage with the said pinion and means to operate the

sector so that it will engage the pinion and make the required feed and remain in gear therewith when the nipper commences to recede from the detaching rollers to turn the 15 feed roller backwards until a desired amount of the previously fed material has been drawn back into the nipper and then disengage.

In testimony whereof I have affixed my 20 signature.

J. W. NASMITH.
